[57] CLAIM

The ornamental design for a stackable and nestable box, as shown and described.

DESCRIPTION

FIG. 1 is a perspective view of a stackable and nestable box showing our new design;

FIG. 2 is a left side elevational view thereof, with the right side being a mirror image thereof.

FIG. 3 is a front elevational view thereof.

FIG. 4 is a rear elevational view thereof.

FIG. 5 is a top plan view thereof.

FIG. 6 is a bottom plan view thereof.

FIG. 1

FIG. 2

FIG. 3

FIG. 4

FIG. 5

FIG. 6
